(57) **CLAIM**

The ornamental design for a medical thread, as shown and described.

DESCRIPTION

1. Medical thread

1.1 : Perspective

1.2 : Front

1.3 : Back

1.4 : Left

1.5 : Right

1.6 : Top

1.7 : Bottom

Reproduction 1.1 is a perspective view of the medical thread; reproduction 1.2 is a front view thereof; reproduction 1.3 is a back view thereof; reproduction 1.4 is a left view thereof; reproduction 1.5 is a right view thereof; reproduction 1.6 is a top view thereof; reproduction 1.7 is a bottom view thereof; this design is a medical thread that can be inserted into the skin of the human body; this design is repeatedly formed along a longitudinal direction. In reproductions 1.1-1.5, the medical thread is shown with a sym-

(Continued)

bolic break line in its length. The appearance of any portion of the article between the break lines forms no part of the claimed design.

1 Claim, 7 Drawing Sheets
